UNITED STATES PATENT OFFICE

104,968

DESIGN FOR AN AUTOMOBILE ROOF AERIAL

Roman Kopanski, Cleveland, Ohio, assignor to
The Ward Products Corporation, Cleveland,
Ohio, a corporation of Ohio

Application February 19, 1937, Serial No. 67,752

Term of patent 7 years

To all whom it may concern:

Be it known that I, Roman Kopanski, a citizen
of the United States and a resident of Cleveland,
in the county of Cuyahoga and State of Ohio,
have invented a new, original, and ornamental
Design for an Automobile Roof Aerial, of which
the following is a specification, reference being
had to the accompanying drawing, forming a
part thereof, in which

The figure is an elevation of an automobile
roof aerial embodying my new design.

I claim:

The ornamental design for an automobile roof
aerial, as shown.

ROMAN KOPANSKI.
